PORTABLE ELECTRIC FOOD MIXER

Raymond H. Andresen, Chicago, Ill.

Application November 10, 1948, Serial No. 149,554

Term of patent 7 years

(Cl. D44—1)

To all whom it may concern:

Be it known that I, Raymond H. Andresen, a citizen of the United States, residing at Chicago, in the county of Cook and State of Illinois, have invented a new, original, and ornamental Design for a Portable Electric Food Mixer, of which the following is a specification, reference being had to the accompanying drawing, forming a part thereof.

In the drawing:

Fig. 1 is a side view, in elevation, of a portable electric food mixer, showing my new design;

Fig. 2 is a front view, in elevation; and

Fig. 3 is a top end view.

The dominant features of my design reside in those portions shown in full lines.

I claim:

The ornamental design for a portable electric food mixer, substantially as shown and described.

RAYMOND H. ANDRESEN.
